PRINTING PRESS INKING MECHANISM

Frank A. Foster, Maywood, Ill., assignor to The
Goss Printing Press Company, Chicago, Ill., a
corporation of Illinois

Application August 26, 1937, Serial No. 160,940

19 Claims. (Cl. 101—365)

The invention relates to new and useful improvements in ink supplying mechanisms for printing presses, and more particularly to such improvements in the ink fountain, fountain roller and associated parts of rotary printing presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:

Fig. 1 is a plan of an inking mechanism embodying my invention;

Fig. 2 is a fragmentary section on line 2—2 of Fig. 1;

25 Fig. 3 is a similar view with the parts in different positions;

Fig. 4 is an enlarged fragmentary section on line 4—4 of Fig. 1;

Fig. 5 is an enlarged fragmentary section on line 5—5 of Fig. 1;

Fig. 6 is a detached elevation of the ink fountain looking at it from the left in Fig. 1;

Fig. 7 is a broken rear elevation of the ink fountain looking at Fig. 1 from the bottom;

30 Fig. 8 is a detached detail view of the spacing and holding member located within the ink fountain; and

Fig. 9 is a similar view of the spacing and holding member located outside the ink fountain.

40 Objects of the invention are to provide an ink fountain mechanism which is of simple and sturdy construction, accurate and reliable in operation, and which may be easily and quickly cleaned. To this end, and in accordance with certain features

45 of the invention, a fountain roller is journaled in permanent position on the press frame and preferably directly in the side frames of the press and a support for the fountain knife blade is also carried by the press frame, and the fountain itself, preferably of light sheet material, is itself bodily insertable and removable, and may be quickly and easily removed and replaced, without disturbing the fountain roller or knife. Other features and advantages of the invention will be

55 pointed out in the following detailed description,

and it will be understood that the foregoing general description and the following detailed description as well are illustrative and exemplary but are not restrictive of the invention.

Referring now in detail to the embodiment of the invention illustrated by way of example in the accompanying drawings, the fountain roller is journaled in the vertical side frames of the press, and as embodied (Figs. 1, 2 and 3) the fountain roller 1 has its projecting shaft ends 2 and 3 journaled each in a pair of spaced apart collars 4 and 5 fitting within and at either end of a cylindrical sleeve or bushing 6. The bushings 6 are fitted in corresponding cylindrical openings in the vertical side frames 7 and 8 of the press. The outer ends of the bushings 6 are formed into flat flanges 11, which abut on the exterior faces of bosses formed on the outside of the vertical frame members 7 and 8. The bushings are held firmly in position by tap bolts 12 which pass through the flanges, and are threaded into the side frames. The inner ends of the bushings 6 fit to the abutting flat ends of the fountain roller 1.

In accordance with certain features of the invention, the ink fountain itself is separately removable from and insertable into operating position with reference to the fountain roller. The ink fountain is preferably of sheet metal or other light construction, and as embodied comprises a body portion 18, having flaring, and somewhat inclined, front and rear walls 19 and 20 and a forwardly and downwardly inclined bottom 21, and flat inwardly and downwardly inclined ends 22 and 23. The end walls 22 and 23 have cut-out portions 24 of a width substantially equal to the diameter of the bushing 6, the lower part of the openings being on substantially the radius of the bushing, so that the end walls will fit snugly to the bushing when the fountain is in position about the roller.

The means for holding the fountain firmly and accurately in position while permitting its quick removal and reinsertion comprise (Figs. 1, 2, 3 and 4) a pair of rigid plates 27 (Figs. 1, 2, 4 and 8), which are of beveled vertical cross section, decreasing in thickness from the top downwardly on the side toward the corresponding end wall of the fountain, and are located within and their inclined sides abut against the inside faces of the vertical ends 22 and 23, respectively, of the ink fountain. Plates 27 extend entirely across the ends of the ink fountain and have their front and rear edges abutting against the front and rear walls 20 and 18 of the ink fountain. The

plates have circular apertures 28 therein, which fit snugly about the bushings 6, which extend inwardly through the recesses or openings 24 in the end walls 22 and 23 of the fountain and fit 5 against the flat end of the fountain roll 1, as shown in Figs. 2 and 3. Set screws 29 are threaded into apertures 30 in the tops of the plates 27 and enter and press against key-ways 35 in the bushings 6, and hold the plates 27 firmly to the 10 bushing, and against the insides of the vertical ends 22 and 23 of the fountain, in proper assembled position. Loose on the threaded part of each bushing 6, respectively, and on the exterior 15 of the side walls 22 and 23, respectively, of the fountain is a cylindrical spacing and holding washer 33, which is tapered in vertical cross section increasingly from the top to the bottom on one side with the same inclination as the member 27 and the adjacent end wall of the fountain, but in the reverse direction. This washer can 20 slide freely along the bushing, but is held from rotation by a key or spline 34, working in a key-way 35, extending longitudinally in the threaded part of the bushing 6. Cooperating with the foregoing is a nut 38 threaded on the bushing 6 exteriorly to the spacing and holding washer 33.

Means are provided for temporarily positioning and supporting the ink fountain preparatory to permanently fastening it in operative position by 30 means of the mechanism just described, and as embodied, there is formed on the outside of each of the end walls 22 and 23 of the fountain a vertically-disposed bar 40, and each of these bars has a pin 41 projecting outwardly from the upper part thereof. Formed on the under side of the fountain plate support 47, later to be described in detail, is a lug 42 from which is pivotally suspended a latch lever 43, having a notch or recess 44 formed therein. The various parts of 40 the permanent fastening means for the fountain are in approximately the position of Fig. 3 when the fountain is returned to position and is lifted upwardly past the position shown in Fig. 3 to that shown in Fig. 4. The levers 43 are then moved 45 clockwise and the recesses or hooks 44 engage beneath the pins 41, as shown in Fig. 4, at which time the straight top edges of the end plates of the fountain fit snugly beneath the fountain knife support 47, thereby accurately positioning 50 the fountain. To firmly fasten the fountain in position, the spacing washers 33 are moved against the outside of the corresponding end walls 22 and 23 of the fountain, and the nuts 38 are screwed up tight, when the parts are in the position shown in Fig. 2, the end plates of the fountain are clamped between the members 27 and 33, and the fountain is held firmly in position, and the openings in the end walls are sealed by the plates 27, and the fountain may be run as full of 55 ink as may be desired without leakage occurring 60 about the fountain shaft.

In accordance with one feature of the invention, the fountain knife supporting means are mounted on the machine frame, and as shown a 65 horizontal plate 47 extends across the press, and has upwardly extending bracket plates 48 and 49 at either end, the outer surfaces of these plates fitting against the inner faces of the side frames, and the plates are fastened to the side frames by 70 tap bolts 50 which pass therethrough and are screw-threaded into the frames. Beneath the horizontally-extending plate 47 is a supporting plate 53, and the fountain knife 54 is mounted between these plates and screw-bolts 55 pass 75 through plate 53 and are screw-threaded into

the bar 47 to hold the parts firmly in position. Formed across the front side of bar 47, and extending forwardly and upwardly therefrom, is the inclined bar 56 through which are screw-threaded a plurality of adjusting screws 51, the points of 5 which bear upon the knife 54 and adjust the pressure of the knife upon the fountain roller 1.

The invention in its broader aspects is not limited to the specific mechanisms shown and described but departures may be made therefrom within the scope of the accompanying claims without departing from the principles of the invention and without sacrificing its chief advantages.

What I claim is:

1. A rotary printing press inking mechanism including in combination a fountain roller journaled in the press frame, an ink fountain cooperating therewith, means mounted on the fountain roller shaft for supporting the ink fountain 20 and means for attaching the fountain to said supporting means and detaching it therefrom whereby it may be removed independently of the fountain roller.

2. A rotary printing press inking mechanism including in combination a fountain roller journaled in the press frame, a fountain knife support carried by the press frame, an ink fountain, means supported by the fountain roller shaft for supporting the ink fountain and means for attaching the fountain to said supporting means and detaching it therefrom whereby it may be removed independently of the fountain roller and knife support.

3. A rotary printing press inking mechanism including in combination a fountain roller journaled in the press frame, a separately removable ink fountain, means concentric with the fountain roller for supporting the ink fountain in operative relation to the fountain roller, and means for attaching the ink fountain to said supporting means and detaching it therefrom.

4. A rotary printing press inking mechanism including in combination a fountain roller journaled in the press frame, a cooperating fountain 45 knife support carried on the press frame, a separate ink fountain, and means concentric with the fountain roller for supporting the fountain in operative relation with the roller and means for attaching the fountain to and detaching it 50 from said supporting means, thereby permitting its removal and insertion without disturbing the roller and knife.

5. A rotary printing press inking mechanism including in combination a fountain roller, means 55 at either end of the fountain roller for journaling the roller on the press frame, an ink fountain, and means at either end thereof for detachably suspending the fountain from said journal means at either end of the fountain roller.

6. A rotary printing press inking mechanism including in combination a pair of stationary sleeves mounted in the side frames of the press, a fountain roller journaled in the sleeves, and an ink fountain supported by the sleeves.

7. A rotary printing press inking mechanism including in combination a pair of stationary sleeves mounted in the side frames of the press, a fountain roller journaled in the sleeves, and an ink fountain removably suspended from said 70 sleeves.

8. A rotary printing press inking mechanism including in combination a fountain roller, an ink fountain, suspension means for the fountain comprising a threaded support, a plurality of 75

5 side by side members, one at least of which is screw-threaded on said support, said members being adapted to clamp the end walls of the ink fountain to hold it in operative relation with the fountain roller.

9. A rotary printing press inking mechanism including in combination a fountain roller, an ink fountain, bearing means in which the fountain roller is journaled, said bearing means including a screw-threaded support, a plurality of members mounted on said support, one at least of which is screw-threaded on said support, said members being adapted to clamp the end walls of the ink fountain to hold it in operative relation with the fountain roller.

10. A rotary printing press inking mechanism including in combination a fountain roller, a removable and replaceable ink fountain having recesses in its end walls adapted to receive the shafts of the fountain roller, and members encircling the roller shaft and means for pressing said members firmly against the end walls of the ink fountain to form an ink seal about the roller shaft.

11. A rotary printing press inking mechanism including in combination a fountain roller, a removable and replaceable ink fountain having recesses in its end walls adapted to receive the shafts of the fountain roller, and members encircling the roller shaft and means for pressing said members and the end walls of the fountain together to support the fountain and form an ink seal about the roller shaft.

12. A rotary printing press inking mechanism including in combination sleeves supported in the side frames of the press and having an external screw thread, a fountain roller journaled in said sleeves, a removable ink fountain having its end walls recessed to receive said sleeves, and means for supporting the ink fountain including a plurality of members mounted on said sleeves, at least one of said members being in threaded engagement with its sleeve, said members being adapted to clamp the end wall of the ink fountain between them.

13. A rotary printing press inking mechanism including in combination sleeves supported in the side frames of the press, the sleeves having external screw threads and a key-way, a fountain roller journaled in said sleeves, a removable ink fountain having its walls recessed to receive said sleeves, and means for supporting the ink fountain including a plurality of members mounted on said sleeves, at least one of said members being in threaded engagement with its sleeve and another member being in engagement with the key-way, said members being adapted to clamp the end wall of the ink fountain between them.

14. A rotary printing press inking mechanism including in combination sleeves supported in the side frames of the press and having an external screw thread, a fountain roller journaled in said sleeves, a removable ink fountain, and means for

supporting the ink fountain including a plurality of members mounted on said sleeves, at least one of said members being in threaded engagement with its sleeve, said members being adapted to clamp the end wall of the ink fountain between them.

15. A rotary printing press inking mechanism including in combination sleeves supported in the side frames of the press, the sleeves having external screw threads and a key-way, a fountain roller journal in said sleeves, a removable ink fountain, and means for supporting the ink fountain including a plurality of members mounted on said sleeves, at least one of said members being in threaded engagement with its sleeve and another member being in engagement with the key-way, said members being adapted to clamp the end wall of the ink fountain between them.

16. A rotary printing press inking mechanism including in combination a fountain roller journaled in the press frame, a fountain knife support carried by the press frame, a removable ink fountain, and means for supporting the fountain from the fountain roller shaft and in operative relation with the roller and knife and with the top edges of the end walls of the fountain abutting on the bottom surface of the knife support.

17. A rotary printing press inking mechanism including in combination a fountain roller journaled in the press frame, a removable ink fountain, and means at either end of the fountain for suspending it both from the fountain roller shaft and from the frame in operative relation with the fountain roller and devices for attaching the fountain to and detaching it from both suspending means.

18. A rotary printing press inking mechanism including in combination a pair of stationary sleeves mounted in the side frames of the press, a fountain roller journaled in the sleeves, a removable ink fountain, means mounted on the press at either end of the ink fountain for suspending it in position, including a plurality of members mounted on each of said sleeves and means for clamping said members with the end walls of the fountain between them to hold it firmly in position.

19. A rotary printing press inking mechanism including in combination a pair of stationary screw-threaded sleeves mounted in the side frames of the press, a fountain roller journaled in the sleeves, a removable ink fountain, having its end walls recessed to receive the roller shaft, pivoted hooks at either end of the ink fountain for suspending it in position, and a plurality of members mounted on each of said sleeves, one at least of said members being in screw-threaded engagement with its sleeve, said members being adapted to clamp the end walls of the fountain between them to hold it firmly in position and to form ink seals about the roller shaft.

FRANK A. FOSTER.
